UNITED STATES PATENT OFFICE

WILLIAM L. GRATHWOL, OF STRATFORD, CONNECTICUT

VACUUM CLEANER FOR AUTOMOBILES

Application filed December 16, 1926. Serial No. 155,234.

This invention relates to a vacuum cleaner for automobiles adapted to be operated by utilization of the engine exhaust, and the general object of the invention is to produce a vacuum cleaner which will be an improvement over the disclosures of patent to Leathers, No. 1,499,937, granted July 1, 1924, and my pending application for patent, Serial No. 87,938, filed February 12, 1926.

10 A more specific object is to provide a vacuum cleaner of the present character which is adapted to be directly connected with the main exhaust line of an engine, and which is provided with improved mechanism whereby 15 a vacuum may be easily and readily produced in a pipe connection or conduit, or may be just as easily and readily destroyed.

20 A further specific object is to provide novel, simple, and improved means for positively retaining the vacuum producing mechanism in operative position and for manipulating said mechanism to destroy vacuum in said pipe connection or conduit when the cleaner is to be put out of use.

25 A further specific object is to provide in the vacuum cleaner a fitting of novel, simple and improved construction.

With the above objects in view, as well as others which will appear as the specification 30 proceeds, the invention comprises the construction, arrangement and combination of parts as now to be fully described and as hereinafter to be specifically claimed, it being understood that the disclosure herein is 35 merely illustrative and meant in no way in a limiting sense, changes in details of construction and arrangement of parts being permissible so long as within the spirit of the invention and the scope of the appended claims.

40 In the accompanying drawing forming a part of this specification,

Fig. 1 is a plan view of an automotive vehicle chassis, disclosing one of the running boards and the exhaust line with muffler, and 45 showing the improved cleaner associated with said running board and exhaust line;

Fig. 2 is a detail sectional view, the line 2-2 in Fig. 1 suggesting the location of the section, disclosing a vacuum cleaner hose associated with the conduit of the cleaner;

Fig. 3 is an enlarged elevational view, partially in section, disclosing an exhaust line, the fitting and conduit or pipe connection of the cleaner, the device for fastening the outer end portion of the conduit or pipe connection 55 as to the automotive vehicle running board, and parts associated with the parts mentioned, the exhaust gas accelerator being shown in full and in dotted lines;

Fig. 4 is an elevational view of the fitting 60 as seen from the right in Fig. 3, disclosing a fragmentary part of the mechanism for actuating the exhaust gas accelerator;

Fig. 5 is an elevational view of the device 65 for fastening the outer end portion of the conduit or pipe connection, as to the vehicle running board, as seen from the right in Fig. 3, disclosing fragmentary parts of the conduit or pipe connection and of the mechanism 70 for actuating the exhaust gas accelerator; and

Fig. 6 is a fragmentary elevational view, 75 partially in section, disclosing a modified form of fitting associated with an exhaust line and a conduit or pipe connection.

With respect to the drawing and the characters and numerals of reference thereon, A denotes an automotive vehicle chassis, B the exhaust line of the engine of said vehicle, C a muffler in said exhaust line, D a running 80 board of said chassis, and 10 represents, generally, the vacuum cleaner of the invention, which is, as disclosed, associated with the exhaust line and running board.

Of the vacuum cleaner, 11 is a fitting 85 secured in the exhaust line. Clearly, the fitting could be secured at the end of the exhaust line. As shown, the fitting consists of two pieces of material tightly surrounding the exhaust line and clamped thereon. One of 90 the pieces of material 12 of the fitting is a longitudinal part of a tube, while the other piece 13 consists of a longitudinal part of a tube having a pocket, cavity, or depression 14 which is in communication with a hollow 95 pipe 15 adapted to receive a conduit or pipe connection 16, the conduit or pipe connection being secured to the hollow pipe in any convenient or suitable manner.

The part tubes 12 and 13 are clamped upon 100

the exhaust line to make a fluid tight fitting in the manner best disclosed in Figs. 3 and 4. The piece of material or part tube 12 includes oppositely disposed, outwardly positioned shoulders 17, one adjacent each longitudinal edge or margin 18 of said part tube 12 and desirably perpendicular thereto, and the piece of material or part tube 13 includes oppositely disposed, inwardly positioned shoulders 19, one adjacent each longitudinal edge or margin 20 of said part tube 13 and complementary to a shoulder 17. The piece of material 12 also has lugs 21 beyond each shoulder 17, each lug 21 being complementary to a lug 22 upon the piece of material 13 and beyond each shoulder 19. Numeral 23 designates screws, one passing through each lug 21 and entering a lug 22 for drawing the part tubes 12 and 13 toward each other. The arrangement is such that when the screws are drawn home, there is a snug fit of the shoulders 17 and 19, respectively, against each other to provide fluid tight joints at the locations indicated 24. The opposite end portions of each of said part tubes 12 and 13 are provided with inwardly extending part or semi-annular flanges, which, when the part tubes 12 and 13 are assembled, furnish annular flanges designated 25 at the inner ends 30 of pockets 26 of the fitting adapted to receive the exhaust line. In practice, the exhaust line pipes snugly fit the pockets 26 and rest against the annular flanges 25 to provide fluid tight joints at the locations represented 27. It will be evident that the arrangement as illustrated and described makes provision for clamping the pieces of material 12 and 13 upon the exhaust line as tightly as may be desirable, the shoulders 17 and 19 sliding over each other and interlapping more or less to make fluid tight joints at the locations 24, and the exhaust line piping being snugly grasped by the end portions of the fitting and resting against the annular flanges 25 thereof to make fluid tight joints at the locations 27, thus precluding the necessity for packing of any sort.

The end 28 of the conduit or pipe connection 16 spaced from the fitting 11 is, for convenience, preferably secured, as by a special device 29, to the lower face of the running board D, although said end 28 could be otherwise situated. The special device 29 may comprise a clamp 30 about the conduit or pipe connection end 28 and including holes 31 for holding means (not shown) adapted to enter the lower face of the running board.

The hollow pipe 15 is adapted to be practically covered normally (when the vacuum cleaner is out of use), to preclude noticeable communication between the conduit 16 and the exhaust line, as by an exhaust gas accelerator 32 fixed upon a shaft 33 rotatably supported in the fitting 11, said accelerator being disclosed in Fig. 3 in dotted lines as practical-

ly cutting off communication between the pipe 15 and the exhaust line.

The exhaust gas accelerator 32 is adapted to be normally situated (as in dotted lines in Fig. 3) so that the normal passage 34 through the fitting is at least as large in diameter as is the passage 35 through the exhaust line next adjacent the fitting (to the right in Fig. 3), and said accelerator is adapted to be swung to its full line position of Figs. 3 and 4, with its marginal portion engaging approximately the full inner circumference or perimeter of the fitting, in order that the cleaner may operate. For so swinging said accelerator I provide a lever 36 fixed upon the shaft 33, and an operating rod 37 having one of its ends pivoted as at 38 to said lever 36 and its end portion 39 opposite said lever slidably arranged in the special device 29. The clamp 30 may include a guide way 40 for the operating rod 37, and a spring 41 upon the device 29 and engaging the rod 37 may provide means for yieldably situating said rod in said guide way. See Figs. 3 and 5. A protuberance 42 upon the clamp 30 may provide a rest for a bent over part 43 of the operating rod 37 when situated in the operative position of the vacuum cleaner. See Fig. 5.

The accelerator 32 is provided with an opening 44 adapted to provide a venturi 45 positioned approximately centrally of the exhaust line when said accelerator is in the operative position of the vacuum cleaner, as very clearly disclosed in Figs. 3 and 4, the venturi being disposed in the direction of the flow of exhaust gases through said exhaust line, as indicated by the arrow in said Fig. 3.

Numeral 46 denotes a cleaner hose adapted to be received in the outer end 28 of the conduit or pipe connection 16, as in Fig. 2.

The manner in which the vacuum cleaner functions is obvious. When the parts are as shown in dotted lines in Fig. 3, the exhaust outlet is of the same cross-sectional area as is the outlet through the fitting 11, and incidentally, the conduit 16 is practically out of communication with the exhaust line. When the parts are as shown in full lines in said Fig. 3, or in Fig. 4, there is communication between the conduit and the exhaust line. At the same time, the exhaust gas outlet through the fitting and past the accelerator 32 is restricted to the venturi 45. When the passage past the accelerator is not restricted, there is no suction created in the exhaust line, but when the passage through the fitting is restricted to the venturi, there is a corresponding acceleration in the velocity of exhaust gases passing through said fitting at the location adjacent the pocket, cavity, or depression 14 adapted to create a suction, and, the conduit 16 now being open to the exhaust line, said suction will tend to create a vacuum in said conduit which will be satisfied through the cleaner hose.

Clearly, when the accelerator 32 is positioned as in dotted lines in Fig. 3, there is no vacuum in the exhaust line or fitting 11 adjacent the hollow pipe 15, but the moment the accelerator is swung to the operative position of the cleaner, the velocity of exhaust gases through the venturi is greatly increased, to produce vacuum in and about the pocket, cavity, or depression 14, which vacuum must be satisfied via the cleaner hose, as will be evident.

When the operating rod is in its full line position as in Fig. 5, the bent over part 43 thereof engaging the protuberance 42 and the spring 41 yieldably holding said operating rod against a wall of the guide way of the device 29, the exhaust gases cannot displace the accelerator 32 from its proper operating position as in Fig. 3. When the operating rod is in its dotted line position as in Fig. 3, or Fig. 5, the spring 41, in cooperation with the guide way 40, suffices to hold the accelerator against accidental displacement from its intended inoperative position.

In Fig. 6 I have disclosed an exhaust line B', a conduit or pipe connection 16', and a fitting 11' having relation which is considerably like the relation between the exhaust line B, the conduit 16, and the fitting 11 as before described. In the present instance, the fitting 11' includes a hollow body 47, of diameter not much greater than the diameter of the exhaust line B', removable or otherwise secured upon said exhaust line as at 48. The fitting 11' also includes a tapered pipe 49 providing a venturi 45' positioned centrally of the hollow body 47 adjacent the outlet 50 thereof, said tapered pipe leading from the conduit or pipe connection 16' and being removably threaded upon the conduit or pipe connection as at 51, or secured to said conduit or pipe connection in some other suitable fashion.

The manner in which the vacuum cleaner of Fig. 6 functions is obvious. Exhaust gases passing through the exhaust line B' accelerate in passing the venturi 45' to create vacuum in the tapered pipe 49, which vacuum must necessarily be satisfied via the conduit or pipe connection 16'.

What I claim is:

1. In an automotive vehicle, a normally unobstructed passage for exhaust gases, a conduit adapted to communicate with said passage, a venturi capable of restricting the area of said passage adjacent said conduit, said venturi normally being situated without said passage, and means for inserting said venturi into said passage.
2. In an automotive vehicle, a passage for exhaust gases, a conduit adapted to communicate with said passage, a venturi for restricting the area of said passage adjacent the mouth of said conduit, and means of which said venturi is a part for practically closing

communication between said conduit and passage.

3. In an automotive vehicle, a passage for exhaust gases, a conduit, and means including a venturi for restricting the cross-sectional area of said passage and for simultaneously opening communication between said conduit and passage. 70

4. In an automotive vehicle, a passage for exhaust gases, a conduit, and means including a venturi for restricting the cross-sectional area of said passage and for simultaneously opening communication between said conduit and a portion of said passage adapted to receive exhaust gases after they have passed 80 said venturi. 75

5. In an automotive vehicle, a passage for exhaust gases, a conduit, and means including a venturi in said passage adjacent the mouth of said conduit for restricting the cross-sectional area of said passage and for simultaneously opening communication between said conduit and passage at a location adjacent said venturi and to which said exhaust gases are adapted to travel when past said venturi. 90

6. In an automotive vehicle, a passage for exhaust gases, a conduit, an exhaust gas accelerator in said passage adjacent the mouth of said conduit, said accelerator being constructed to provide a venturi, and means for manipulating said accelerator to restrict said passage to said venturi and to simultaneously open communication between said conduit and passage. 95

7. In an automotive vehicle, a passage for exhaust gases, a conduit, an exhaust gas accelerator in said passage adjacent the mouth of said conduit, said accelerator being constructed to provide a venturi and being adapted to normally practically close said conduit from said passage, and means for manipulating said accelerator to restrict said passage to said venturi and to open said conduit to said passage. 100

8. In an automotive vehicle, a passage for exhaust gases, a conduit, an exhaust gas accelerator in said passage adjacent the mouth of said conduit, said accelerator being constructed to provide a venturi and being adapted to normally approximately close said conduit from said passage, and means for manipulating said accelerator to restrict said passage to said venturi and to open said conduit to said passage at a location adjacent said venturi and adapted to receive exhaust gases from said venturi. 110

9. In an automotive vehicle, an exhaust outlet including a passage for exhaust gases and a pocket in said passage, a conduit adapted to communicate with said passage, and means in said pocket normally practically closing said conduit from said passage, said means being constructed to provide a venturi and being adapted to be manipulated to afford communication between said conduit 125

130

- and passage and to simultaneously restrict said passage to said venturi adjacent said pocket and the location of communication between said conduit and passage.
- 5 10. In an automotive vehicle, an exhaust outlet including a passage for exhaust gases and a pocket in said passage, a conduit adapted to communicate with said passage, an exhaust gas accelerator in said pocket, said 10 accelerator being constructed to provide a venturi, and means for manipulating said accelerator to afford free communication between the conduit and passage and to simultaneously restrict said passage to said venturi 15 and thus increase the velocity of exhaust gases adapted to travel past the mouth of said conduit.
11. In an automotive vehicle, an exhaust outlet, a conduit adapted to communicate therewith, and means between said conduit and exhaust outlet adapted to normally restrict said conduit, said means being constructed to provide a venturi and being adapted to be manipulated to allow communication 25 between said conduit and exhaust outlet and to simultaneously restrict the area of said exhaust outlet to said venturi at a location adjacent the location of communication between said conduit and outlet.
- 30 12. In an automotive vehicle, an exhaust outlet, a conduit adapted to communicate therewith, an exhaust gas accelerator between said conduit and exhaust outlet adapted to normally restrict said conduit, said accelerator being constructed to provide a venturi, and means for manipulating said accelerator to afford communication between said conduit and exhaust outlet and to simultaneously restrict the area of said exhaust outlet to said 35 venturi at a location adjacent the location of communication between said conduit and outlet.
13. A device of the character described, comprising a fitting adapted to be secured to the exhaust line of an automotive vehicle engine, a conduit adapted to communicate with said fitting, an exhaust gas accelerator adapted to normally restrict communication 45 between said conduit and fitting, said accelerator being constructed to provide a venturi, and means for causing said accelerator to restrict said fitting to said venturi and to simultaneously afford communication between said conduit and fitting.
- 50 14. A device of the character described, comprising a fitting having a passage for exhaust gases, a conduit adapted to communicate with said passage, an exhaust gas accelerator adapted to normally restrict communication 55 between said conduit and passage, said accelerator being constructed to provide a venturi, and means for adjusting said accelerator to afford communication between said conduit and passage and to simultaneously restrict the cross-sectional area of said passage to said venturi.
15. A device of the character described, comprising a member having a passage for exhaust gases, a conduit adapted to communicate with said member, and means including a venturi adapted to be inserted in said passage to afford communication between the conduit and passage tending to create a vacuum in said conduit by reason of the travel of exhaust gases through said passage and to be removed from said passage to rid said conduit of vacuum. 70
16. In an automobile vehicle, an exhaust gas outlet, a fitting associated with said outlet and having a passage for exhaust gases, a conduit adapted to communicate with said passage, the conduit being secured upon a fixed part of the vehicle and having an opening adapted to receive a vacuum hose, a pivoted and adjustable accelerator between said conduit and passage adapted to be positioned to restrict communication between the conduit and passage, or to open communication 75 between the conduit and passage and restrict the passage, and means for manipulating said accelerator, said means comprising a lever fixed to the axis of said accelerator, an operating rod pivoted to said lever, a guide way on a fixed part of the vehicle for said operating rod, and devices associated with said guide way for fastening said operating rod in the operative position of said accelerator. 80
17. In an automotive vehicle, an exhaust gas outlet, a fitting associated with said outlet and having a passage for exhaust gases, a conduit adapted to communicate with said passage, the conduit being secured upon a fixed part of the vehicle and having an opening adapted to receive a vacuum hose, a pivoted and adjustable accelerator between said conduit and passage adapted to be positioned to restrict communication between the conduit and passage, or to open communication 85 between the conduit and passage and restrict the passage, and means for manipulating said accelerator, said means comprising a lever fixed to the axis of said accelerator, an operating rod pivoted to said lever, a guide way on a fixed part of the vehicle for said operating rod, and devices associated with said guide way for fastening said operating rod in the operative position of said accelerator. 90
18. In an automotive vehicle, an exhaust gas outlet, a fitting associated with said outlet and having a passage for exhaust gases, a conduit adapted to communicate with said passage, the conduit being secured upon a fixed part of the vehicle and having an opening adapted to receive a vacuum hose, a pivoted and adjustable accelerator between said conduit and passage adapted to be positioned to restrict communication between the conduit and passage, or to open communication 95 between the conduit and passage and restrict the passage, and means for manipulating said accelerator, said means comprising a lever fixed to the axis of said accelerator, an operating rod pivoted to said lever, a guide way on a fixed part of the vehicle for said operating rod, and devices associated with said guide way for fastening said operating rod in the operative position of said accelerator. 100
19. In an automotive vehicle, an exhaust gas outlet, a fitting associated with said outlet and having a passage for exhaust gases, a conduit adapted to communicate with said passage, the conduit being secured upon a fixed part of the vehicle and having an opening adapted to receive a vacuum hose, a pivoted and adjustable accelerator between said conduit and passage adapted to be positioned to restrict communication between the conduit and passage, or to open communication 105 between the conduit and passage and restrict the passage, and means for manipulating said accelerator, said means comprising a lever fixed to the axis of said accelerator, an operating rod pivoted to said lever, a guide way on a fixed part of the vehicle for said operating rod, and devices associated with said guide way for fastening said operating rod in the operative position of said accelerator. 110
20. In an automotive vehicle, an exhaust gas outlet, a fitting associated with said outlet and having a passage for exhaust gases, a conduit adapted to communicate with said passage, the conduit being secured upon a fixed part of the vehicle and having an opening adapted to receive a vacuum hose, a pivoted and adjustable accelerator between said conduit and passage adapted to be positioned to restrict communication between the conduit and passage, or to open communication 115 between the conduit and passage and restrict the passage, and means for manipulating said accelerator, said means comprising a lever fixed to the axis of said accelerator, an operating rod pivoted to said lever, a guide way on a fixed part of the vehicle for said operating rod, and devices associated with said guide way for fastening said operating rod in the operative position of said accelerator. 120
